(57) **CLAIM**

The ornamental design for an aircraft navigation icon for a display screen, as shown and described.

DESCRIPTION

FIG. 1 is a front view showing an aircraft navigation icon for a display screen, shown separately from a portion of the display screen for clarity of illustration, and shown at an enlarged scale; and,

FIG. 2 is a front view of an aircraft navigation icon for a display screen.

The broken line showing of the display screen and various portions thereof are for the purpose of illustrating unclaimed portions and form no part of the claimed design.

1 Claim, 2 Drawing Sheets

FIG. 1

FIG. 2
